UNITED STATES PATENT OFFICE.

HERMANN LEMP, OF LYNN, MASSACHUSETTS, ASSIGNOR TO ELIHU THOMSON, OF SWAMPSCOTT, MASSACHUSETTS.

MOTION-CHECKING DEVICE.

SPECIFICATION forming part of Letters Patent No. 692,875, dated February 11, 1902.

Application filed November 17, 1900. Serial No. 36,866. (No model.)

To all whom it may concern:

Be it known that I, HERMANN LEMP, a citizen of the United States, residing at Lynn, county of Essex, State of Massachusetts, have 5 invented certain new and useful Improvements in Motion-Checking Devices, (Case No. 1,895,) of which the following is a specification.

In my prior applications Serial No. 686,063, filed July 15, 1898, and Serial No. 23,990, filed July 18, 1900, and renewed November 1, 1901, Serial No. 80,823, I have described and claimed a motion-checking device wherein the movable member or members of an organization 10 are prevented from transmitting strains to the operating device or handle. The checking device illustrated consists of a hydraulic lock which is controlled by valves that are under the direct control of the operating-handle 15 and which are so arranged that the first portion of the angular movement of the handle releases the lock, and continued movement changes the position or relation of the said members. In the structures referred to 20 in these cases there is of necessity a limited amount of lost motion between the operating-handle and the member or members to be moved.

The present invention relates to the same 25 general subject-matter outlined above; but instead of arranging the valve-mechanism so that it is controlled by the ordinary movements of the handle a valve is employed, which valve is controlled by a device that necessitates an action other than that required 30 for moving the members of the organization with respect to each other.

Referring to the accompanying drawings, 35 which illustrate an embodiment of my invention, Figure 1 is a longitudinal section of the motion-checking device, on an enlarged scale, taken on line 11 of Fig 3. Fig. 2 is a horizontal section taken on line 22 of Fig. 1 looking in the direction of the arrow. Fig. 3 is a plan view 40 of a steering-check on a somewhat-reduced scale. Fig. 4 is a vertical section of the piston. Fig. 5 is a transverse section of the piston, taken on the line 55 of Fig. 2, looking in the direction of the arrow. Fig. 6 is a horizontal section showing the valve mechanism 45 in the open position. Figs. 7 and 8 are re-

spectively an end elevation and plan view of the piston. Fig. 9 is a plan view of the piston-controlling valve. Figs. 10 and 11 are respectively a side and end elevation of the 55 same. Fig. 12 is a side elevation of the motion-checking device and operating-handle with the latter in section. Fig. 13 is a detail view of the bulb employed for actuating the valve. Fig. 14 is a detail view in plan of a 60 part of the connection between the steering-handle and the wheels. Fig. 15 is a partial elevation of a slight modification. Fig. 16 is an enlarged sectional detail view of the same. Fig. 17 is a further modification wherein a piston 65 is employed instead of a bulb. Figs. 18 and 19 are respectively a rear end and plan view of the steering-handle. Fig. 20 is a front elevation of the same. Fig. 21 is a plan view of the front wheels of a vehicle, showing the improved motion-checking device in position; and Fig. 22 is a modified form of the means 70 for actuating the piston-valves.

Referring to Fig. 1, A represents the main body or casing of the device, which is secured 75 to the fixed axle A' of the vehicle by means of a suitable clamp. When the apparatus is applied to devices other than vehicles the body or base casing is secured to one portion of the apparatus, while the piston or moving 80 part is connected to another of said portions. The casing is provided with a circular chamber, and mounted eccentrically therein is a piston B. The latter is L-shaped and is provided with a valve-receiving chamber B'. 85 This chamber is provided with two concentric enlargements B² B³, and communicating with these enlargements are series of holes B⁶. By means of these holes the normally quiescent fluid in the main chamber is permitted to pass from one side of the piston to the other when the piston-valve C is moved 90 to an operative position. The end of the valve-chamber is closed by means of a screw-threaded plug B⁴. The opposite end of the 95 chamber communicates with a vertically-extending passage B⁵. The upper end of the piston is screw-threaded, and mounted therein is a plug D, which is connected to the air-conveying flexible tube D'. Situated above 100 the piston and provided with a downwardly-extending end E' is a casting E, which closes

the casing A above the piston. The outer surface of the end or extension E' is given the same shape as the interior of the body or casing, while the inner wall is curved concentric with the center of motion of the piston and steering-handle. The casting E is cored out to form a fluid-receiving chamber, which fluid is designed to keep the chambers A² and A³ on opposite sides of the piston full at all times. The casting is provided with a cover E², which is retained in place by screws, as illustrated in Fig. 3. The valve for controlling the operation of the piston is actuated by fluid-pressure and consists of a cylindrical piece having transverse chambers or passages C' and C², which are connected by a passage extending lengthwise of the piston. The right-hand end of the valve is chambered out to receive a coiled extension-spring F, the opposite end of the spring being seated in a cut-away portion of the screw-threaded plug B⁴. When for any reason it is desired to inspect the valve, the screw-threaded plug B⁴ is removed and the parts slipped out endwise. By moving the piston-like valve C forward until the passages C' and C² coincide with the holes B⁶ in the piston the normally quiescent body of fluid will be permitted to flow from the chamber A² to the chamber A³ under the action of the main piston B. As soon as the pressure on the valve is released the coil-spring F tends to move it back to the position shown in Figs. 1 and 2. As soon as this is done the passage of fluid from chamber A² to chamber A³ is interrupted, and the parts are locked.

In a device of this character there is always more or less tendency of the fluid to leak from one chamber to another, also to leak out from the casing through the joints, at the same time admitting a certain amount of air. In order to prevent this, circular chambers G and H are provided. The chamber H communicates with a passage I, formed in the upper surface of the piston, and the chamber G communicates with the chamber formed in casting E. As the piston-valve is moved to the right the fluid in the right-hand end of the piston-chamber B' is forced into the passage I and the chamber H; but as soon as the piston moves to the position shown in the figures it returns to the chamber B'.

Referring to Figs. 12 and 13, J represents the vertically-extending steering-tube, which is connected to the piston through the universal joint J'. Pivotal secured to the upper end of the tube is a tubular steering-lever J². The free end of the steering-lever is expanded to form a cage J³, in which is mounted a tough rubber bulb J⁴. This bulb communicates, by means of the flexible tube D', with the screw-threaded plug D, Fig. 1, that enters the piston. The bulb may or may not have a valve therein, as desired. Surrounding the upper end of the piston and rigidly secured thereto is a lever K, that is connected

to the steering-wheels in any suitable manner. In steering the vehicle the steering-lever J² is swung from one position to another, with the axis of the piston as a center. When the operator desires to move the steering-wheels, he grasps the steering-lever J² and at the same time compresses the bulb J⁴, which in turn forces air or liquid through the pipe D' into the piston and actuates the piston-valve C. On relieving the pressure on the bulb the valve will return to its normal position, thereby interrupting the flow of fluid from the chamber A² to the chamber A³, and the vehicle-wheel or other device to which the motion-checking mechanism may be applied will be locked. By placing the bulb J⁴ within the handle virtually no thought is required on the part of the operator to open and close the valve in steering, since the operator would ordinarily grasp the handle firmly, and this is sufficient to force air enough into the valve-chamber in the piston to actuate the valve.

Referring to Figs. 15 and 16, I have shown a slight modification of my invention, wherein the bulb J⁴ is compressed or actuated by a downward movement of the steering-lever J². The bulb is mounted in a small upright receptacle L, that is secured to the vertically-extending steering-tube J. The steering-lever is pivoted in the ordinary manner, so that it can be thrown forward to permit the operator to take his seat. Formed on a sleeve that is carried by the steering-lever is a projection L', that engages with the top of the bulb and compresses it whenever a downward movement is imparted to the steering-handle. In addition to this a second lug L² is formed on the sleeve, which lug engages with a spring-pressed plunger L³. This plunger normally holds the lug L' in such position that it rests lightly on the bulb, so that when the handle is forcibly depressed sufficient air will be furnished to actuate the piston-valve in the manner described above. In this instance a movement is required which is separate from the steering movement; but since the natural tendency of the operator in steering is to grasp the handle firmly and force it downward slightly it amounts practically to a single movement of the steering-handle to accomplish both the opening of the valve and the moving of the steering-wheel. With this structure, as well as with the one previously described, there is no lost motion between the operating-handle and the moving member of the check.

In Figs. 17 to 20, inclusive, I have illustrated a further modification of my invention, wherein I dispense with the use of a bulb and substitute therefor a piston M, which is actuated by a dog N, that is pivotally secured to the steering-tube J. The steering-lever J² works on the same pivot with the dog N; but it is independent thereof to this extent that it may be thrown forward to permit the operator to take his seat; but the instant that

the handle is depressed the lug N' on the handle engages with the dog and forces it downward. When the dog is depressed, the piston M forces air or liquid through the pipe D' into the piston and actuates the piston-valve C. In order to return the piston M to its normal position, a coiled extension-spring O is employed. Located on the top of the steering-tube is a fork P, which engages with the steering-lever and acts as a guide therefor during its up and down movements. As before stated in connection with Figs. 15 and 16, the natural impulse of the operator is to grasp the steering-handle firmly and at the same time depress it slightly, and this depression serves to operate the valve controlling the piston.

Referring to Fig. 21, I have shown my invention in connection with the steering-wheels 20 of a vehicle. Q represents the steering-wheels, which are mounted on short axles Q', that are pivotally supported by the fixed axle A'. The body or casing A is mounted on the fixed axle A', and the steering-wheels are connected to the lever J² by means of connecting-rods R and lever K. As the steering-lever J² is moved to either side of a given position, the angular position of the steering-wheels is changed, the unlocking and locking being accomplished in a manner previously described.

Referring to Fig. 22, I have shown a slight modification of my invention, wherein B represents the moving piston, which piston is chambered out, and mounted within the chamber is a bulb S, made of rubber or other flexible material. The bulb does not make a tight fit with the interior of the piston at all points. This is to permit the fluid in the chamber on one side of the piston to flow through the piston to the chamber on the other side. The end of the piston is provided with a screw-threaded plug D⁴, through which the bulb S may be inserted or withdrawn. The bulb is provided with two stud-like metal projections U, having enlarged heads which are secured in the body of material forming the bulb. These projections are intended to engage with and open the flap-valves T and T'. These valves are of any ordinary construction, but preferably are hinged at the top, so that they will close by gravity. The bulb is attached to the flexible pipe D', which leads to the bulb in the handle or to the cylinder containing the piston M, as desired. It is evident that this valve may be operated by any suitable means that is capable of supplying fluid under pressure. This modification possesses certain advantages in that the valves T and T' will automatically lock whenever the force exerted by the wheels is greater than that exerted on the steering-lever by the operator. In operating a motion-checking device provided with this modified form of piston air or liquid under pressure is supplied to the bulb through the pipe D'. This causes the bulb to expand, and the projections U force the valves outward, after which the pis-

ton and cylinder may be moved with respect to each other. When the pressure on the bulbs is relieved, the sides of the bulb will assume the position shown, and the valve will close by gravity.

What I claim as new, and desire to secure by Letters Patent of the United States, is—

1. In a motion-checking device, the combination of a moving and a stationary member, a hydraulic lock for holding the parts in fixed relation, a valve, and a fluid-actuated means for moving the valve. 75

2. In a motion-checking device, the combination of a moving and a stationary member, a hydraulic lock for holding the parts in fixed relation, and a bulb actuated by the movement of the hand for creating fluid-pressure to move the valve. 80

3. In a motion-checking device, the combination of a moving and a stationary member, a double-acting lock, for securing the parts, and a valve actuated by fluid-pressure controlling the unlocking of the parts. 85

4. In a motion-checking device, the combination of a moving and a stationary member, a double-acting lock for securing the parts, a valve actuated by fluid-pressure arranged to unlock the parts, and a mechanical means for closing the valve and locking the parts. 95

5. In a motion-checking device, the combination of a casing, a piston mounted therein and arranged to divide the casing into two chambers, a body of fluid for each chamber, a valve actuated by fluid-pressure for controlling the transfer of fluid from one chamber to another, and means for supplying fluid-pressure to actuate the valve. 100

6. In a motion-checking device, the combination of a casing, a piston mounted therein and arranged to divide the casing into two chambers, a body of fluid for each chamber, a valve actuated by fluid-pressure for controlling the transfer of fluid from one chamber to another, and a manually-actuated means for creating a fluid-pressure to actuate the valve. 105

7. In a motion-checking device, the combination of elements movable with respect to each other, an actuator rigidly connected to one of the elements, a lock for securing the elements in fixed relation, a fluid-actuated means for controlling the lock, and manually-actuated means for creating the necessary fluid-pressure. 115

8. In a motion-checking device, the combination of two members movable with respect to each other, a double-acting lock between the members, a handle for moving the members with respect to each other, and a manually-actuated fluid-pressure-creating device for releasing the lock. 125

9. In a motion-checking device, the combination of two members movable with respect to each other, a double-acting lock between the members, a handle for moving the members with respect to each other, and a bulb which has to be compressed prior to the act 130

of moving the members for causing a fluid-pressure to release the lock.

10. In a motion-checking device, the combination of two members movable with respect to each other, a lock for securing the parts against movement, and fluid-actuated means for controlling the lock.

11. In a motion-checking device, the combination of two members movable with respect to each other, a lock for securing the parts against movement, a valve controlling the lock, and a means for furnishing fluid under pressure for actuating the valve.

12. In a motion-checking device, the combination of two members movable with respect to each other, a lock for securing the parts against movement, a valve controlling the lock, a handle for moving the members with respect to each other, and an air-bulb held in a support on the handle for furnishing the necessary pressure to actuate the valve.

13. In a motion-checking device, the combination of a piston, a casing containing a chamber in which the piston is movable, a body of normally quiescent fluid filling the chamber each side of the piston, a pressure-actuated valve carried by the piston for controlling the transfer of fluid from one side of the piston to the other, and means external to the casing for creating a fluid-pressure and conveying it to the valve.

14. The combination of a casing, a piston dividing the same into two compartments and having a fluid-passage formed therein, a fluid-actuated valve mounted in a chamber in the piston, which chamber communicates with said passage, and external means for supplying fluid under pressure to the passage for actuating the valve.

15. The combination of a casing, a piston working therein, a cylindrical valve mounted in the piston, a coiled spring for pressing the valve in one direction, a removable plug for closing the end of the chamber containing the valve, a passage in the piston communicating

with the valve-chamber, and means for conveying fluid under pressure to the passage for actuating the valve.

16. The combination of a casing, a piston, a valve working within the piston, a passage formed in the piston which extends outside of the casing, and means for supplying fluid under pressure to the passage for actuating the piston.

17. In a motion-checking device, the combination of a casing, a body of normally quiescent fluid therein, a piston, a piston-valve mounted in the piston and arranged to open and close a passage through the same, and a relief-passage into which a certain amount of fluid is forced as the valve is moved.

18. In a motion-checking device for vehicles, the combination of a steering-wheel, an axle, a casing and a piston movable with respect to each other and mechanically connected to the axle and wheel, a body of normally quiescent fluid which fills the casing, a valve for controlling the movement of the fluid within the casing, and a manually-controlled means for creating a fluid to actuate the valve.

19. In a motion-checking device, the combination of members movable with respect to each other, a lock therefor comprising a fluid body, a valve for controlling the transfer of the fluid, and a relief-passage into which fluid is forced by the movement of the valve.

20. In a motion-checking device, the combination of elements movable with respect to each other, a lock, fluid-pressure-actuated means controlling the lock, and manually-actuated means for creating the necessary fluid-pressure to operate the lock-controlling means.

In witness wherof I have hereunto set my hand this 14th day of November, 1900.

HERMANN LEMP.
